UNITED STATES PATENT OFFICE.

GEORGE BLYTHE, OF CHILlicothe, MISSOURI.

IMPROVEMENT IN SAW-FILING MACHINES.

Specification forming part of Letters Patent No. 133,194, dated November 19, 1872.

To all whom it may concern:

Be it known that I, GEORGE BLYTHE, of Chillicothe, in the county of Livingston and State of Missouri, have invented a new and valuable Improvement in Saw-Filing Machines; and I do hereby declare that the following is a full, clear, and exact description of the construction and operation of the same, reference being had to the annexed drawing making a part of this specification, and to the letters and figures of reference marked thereon.

Figure 1 of the drawing is a representation of a top view of my invention. Fig. 2 is a detail view of my invention. Fig. 3 is a vertical section of my invention. Fig. 4 is an end view of my invention. Fig. 5 is a transverse section of my invention.

This invention has relation to a machine for filing the teeth of straight-edged saws; and it consists in the hereinafter-described construction and novel arrangement of the adjustable filing-frame, the saw-clamp, tooth-sizing gage, guide-bed, file-bar, file-holders, and feeding-screw, all substantially as and for the purpose hereinafter more fully specified.

Referring to the accompanying drawing, A designates the ends or legs of the filing-frame, held together by long bolts, B. These bolts have two nuts at each end—one inside and the other outside the end of the frame. The nuts hold the parts A together rigidly, but allow the same to be adjusted to any required distance apart. The tops of the ends A have arms a, which extend back and are recessed to form bearings for a feeding-screw, a¹, which may be operated by a crank on one end of its shaft or by gearing properly arranged and connected therewith. Caps a² are put over the journals of the screw and secured to the arms a by means of bolts a³. The saw-clamp is secured to the front part of the filing-frame, and consists of two parallel bars or jaws, B', secured together, and capable of the necessary adjustment. C designates the guide-bearer, so termed because it supports all the guides. The back part of the guide-bearer has an internally-threaded box, through which the feeding-screw works, and thereby moves the guide-bearer laterally. The upper part of said box, marked d, is cast with the guide-bearer, and has ears d¹. The lower part, marked d², is separate, and is provided also

with ears d³, through which pass screws E, connecting the two parts together. Midway between its ends the sides E' of the guide-bearer are extended laterally, and are constructed with recessed elevations or arches F to receive the saw-clamp, as shown, the inner or under surfaces of the arches resting firmly on said clamp. G represents notches in said arches to let the latter pass over the teeth of the saw. H represents horizontal parallel plates, elevated at the ends of the guide-bearer, and arranged with their upper surfaces exactly on a line with each other. At the ends of these plates longitudinal slots I are cut, and at the middle part of each a hole, I', is formed. The slots hold bolts J having rectangular heads, corresponding to longitudinal grooves in the file-bar, and may be shifted, when necessary, to the holes I'. L represents the file-bar, consisting of a long bar having grooves or slots M extending from each end to near the middle part. The rectangular bolt-heads fit these grooves. When two of the bolts are placed in the holes I', and the file-bar adjusted to them, the file cuts the edges of the teeth straight across; but when the bar is adjusted diagonally and upon two bolts arranged, respectively, at opposite ends and on opposite sides of the guide-bearer, the file cuts the edges obliquely or to a bevel. The nature of the bevel is governed by the positions to which the rectangular-headed bolts are adjusted. K designates the file, and K¹ K² the file-holders. The latter are bolts having flat heads, through which round holes are bored to hold the stem and point of the file. The holes are made round so that the file may be set to cut teeth of any desired pitch. The bolt or file-holder K² receives the stem of the file and passes through a longitudinal slot, K³, in the file-bar, which allows it to be adjusted to any length of file in order to secure the same in a rigid manner. The holder K¹ passes through a hole in the file-bar. Both holders are provided with thumb-nuts m on their upper ends, and are adjustable vertically by means thereof in order that the file may be adjusted to the proper position, the adjustment being high or low according to the length of the teeth of the saw. The holder K¹ must be lowered below the holder K² to compensate for the tapering form of the file. The threads

on the shank of the holders work through nuts m' on the under side of the file-bar. The file-bar is made narrow at its middle part, so that the file may be seen at work by the operator.

In filing, the file is fed from one tooth to the other by means of the feed-screw. The file travels from the handle toward the point of the saw, and vice versa. When the teeth have beveled edges the file, while traveling in one direction, passes to every other tooth; but when the teeth are straight-edged the file passes from one tooth to the next. The file must of course be raised in passing from tooth to tooth. The operation may be accomplished by simply lifting the file-bar and then turning the feed-screw a sufficient distance, or it may be accomplished by lifting the guide-holder, which is arranged to turn on the feed-screw as on a hinge.

N designates a contrivance for gaging or sizing the teeth. It consists of a bent or U -shaped metallic device pivoted to a stem which passes through one side of the guide-holder, and which is adjustable and held at any point by means of a set-screw, O , as shown. The gage is placed above the saw-clamp. The stem has a slot or channel in its lower part to let the saw-edge pass.

The operation of the gage is as follows: The filing is commenced at the side of the machine nearest the gage, the guide-bearer being moved as close to this side as may be required. The pivoted piece n is now raised. One or more teeth are then finished, and the piece n let down so that its forward end shall lie in the bottom of the angular notch between two teeth. Now, according as the remaining teeth

are successively finished, and the guide-holder moved, the piece n rises from one notch and falls into the next, and in this way gages all the teeth to a uniform size with those first cut. The file-bar is operated by taking hold of both ends and running it to and fro in the direction of its length. When the teeth are beveled the file-bar must of course be shifted from one set of rectangular bolts to the other during the operation. The proper length of the teeth is obtained when the file-bar plays evenly over and in contact with the surfaces of the plates holding the rectangular-headed bolts.

What I claim as my invention, and desire to secure by Letters Patent, is—

1. The gage N , in combination with the set-screw o , substantially as specified.
2. In a saw-filing machine, the laterally-adjustable guide-beam E' holding the file-bar L , in combination with the feed-screw a' , substantially as specified.
3. The laterally-adjustable hinged guide-beam, constructed and arranged substantially as specified.
4. The slotted file-bar L , in combination with the slotted plates H and rectangular-headed guide-bolts J , substantially as specified.
5. The tooth-gage N having the hinged self-adjusting device n , and arranged substantially as specified.

In testimony that I claim the above I have hereunto subscribed my name in the presence of two witnesses.

GEORGE BLYTHE.
